UNITED STATES PATENT OFFICE.

EUGENE J. MEYBERG, OF LOS ANGELES, CALIFORNIA.

LIGHTING-FIXTURE.

1,215,299.

Specification of Letters Patent.

Patented Feb. 6, 1910.

Application filed April 8, 1910. Serial No. 89,789.

To all whom it may concern:

Be it known that I, EUGENE J. MEYBERG, a citizen of the United States, residing at Los Angeles, in the county of Los Angeles and State of California, have invented new and useful Improvements in Lighting-Fixtures, of which the following is a specification.

This invention relates to a lighting fixture, and pertains especially to fixtures for 10 semi-indirect lighting.

It is an object of this invention to provide a fixture having a reflector so constructed and disposed with relation to a source of light that a portion of the light rays may 15 pass through said reflector and be reflected from a surface below which the fixture is disposed.

It is another object of this invention to provide a fixture easily assembled and 20 disassembled.

It is a further object to provide a fixture having a removable transparent reflector.

In addition to the broader features of design of a fixture, the invention includes certain specific features of construction by 25 which important advantages are secured in simplicity and convenience of constructing and assembling the fixture.

An embodiment of my invention is illustrated in the accompanying drawing, in which:

Figure 1 is an elevation partly in section of my improved fixture.

Fig. 2 is a view looking upward.

Fig. 3 is an enlarged view of a detail in vertical section.

More specifically, 4 indicates a fixture pipe or conduit suitable for carrying electric wires. A coupling is indicated by 5 and 40 comprises a member of ring form provided with a threaded aperture 6. The aperture 6 is of such size as to receive the pipe 4. Threaded bores 7 are provided on the cylindrical surface of the coupling 5 for receiving 45 set screws. Coupling 5 serves as a support for an annular frame 8 in the form of a shell having an interiorly disposed flange 9 forming a shoulder for supporting a reflector. The frame 8 may have its surface ornamented as found convenient, and may be of 50 such configuration as will be artistic. Arms 11 are secured by means of set screws 7 to the coupling 5 and at their lower ends by suitable screws to the frame 8. De- 55 pending from the coupling 5 is a pipe or

conduit 10 forming in effect a continuation of the pipe 4, and with the pipe 4 forming a fixture support.

Mounted upon the pipe 10 is a bell shaped shell 14 which is provided at its upper end 60 with a collar 12, and means for detachably securing it to the coupling such as a set screw 13. In the walls of the shell 14 are screws 15 threaded in apertures in the wall of the shell. The screws 15 are for the purpose of securing the reflector thereto.

A reflector 16 of conoidal form having at its center an opening through which the lamp socket and bowl supporting shell is adapted to extend, rests at its outer edge 70 upon flange 9. Reflector 16 has an annular lip 17, thereby providing a groove in which the screws 15 may be disposed.

An inverted bowl 18 is secured to the fixture by means of a shell 19 which is provided with a collar 20 to slip over the pipe 10. Secured to shell 19, which is of bell form, and at the edge thereof are downwardly depending arms 22 which extend outwardly. The upper ends of these arms are bent to form hooks 23 which are adapted to engage in apertures 24 formed in the lower peripheral edge of the bell 19. The above construction is one of the important features of my invention in that the hooks 75 on the ends of the supporting arms 22 may be detached from the bell and the bowl 18 readily removed. The arms 22 extend downwardly and outwardly from the shell and are passed through apertures in the bowl 18. 80 The ends of the arms 22 are preferably threaded and have mounted thereon jam nuts 25 adapted to abut the inside surface of the bowl. Balls 26 are provided with threaded apertures which screw upon the 85 arms 22 and are adapted to abut the outside of the bowl 18.

Secured to the pipe 10 and depending therefrom is a lamp socket 27 which is of the usual form and is disposed within the 100 shell 19. The socket is adapted to receive an incandescent lamp 28 which is disposed within the bowl 18. The bowl 18 may be constructed of translucent glass so that a portion of the light will be transmitted and 105 diffused through the bowl and some reflected upwardly.

Light rays coming from the source of light and passing upward above the edge of the bowl will strike the reflector surface 16, 110

some of the light rays being deflected downwardly. Other of these rays pass upwardly through the transparent reflector and to the ceiling, if the fixture is disposed directly below the ceiling. The latter rays are reflected by the ceiling downwardly into the room. There is substantially no obstruction for the light rays which pass through the reflector 16 as the arms 11 are the only portions interposed in the path of the rays. Part of the light rays emanating from the source of light outwardly and impinging upon the surface of the bowl 18 will pass directly through the bowl and illuminate the portions of the room below the fixture. Other of these light rays emanating from the source of light and impinging upon the bowl 18 will be reflected upwardly and strike the transparent reflector 16, some of these passing therethrough to the ceiling and others reflected downwardly into the room.

It is obvious that the light rays by my construction are diffused so that a uniform soft light is produced. The easy disassembling of the fixture 16 is apparent from its construction. The bowl 18 and arms 22 may be unhooked from bell 19 and removed therefrom. The bowl 18 may be removed from the arms 22 by unscrewing the balls 26 and pressing the arms inward out of the aperture. The socket 27 may then be unscrewed from the pipe 10 and shell 19 removed. The set screws 15 are moved out of engagement with the groove in reflector 16 whereupon the shell 14 may be raised. By unscrewing the screws upon the arms 11 which secure the frame 8 to the latter the frame may be dropped and the reflector 16 removed.

What I claim is:

1. In a lighting fixture, the combination with a fixture pipe, of an annular frame provided with an inturned flange; a spider detachably secured to said frame and said fixture support; a reflector of conoidal form having an opening at its center disposed on the flange of said frame; a bowl supporting spider; a shell detachably secured to said fixture and to said bowl supporting spider; and a lamp socket detachably secured to said fixture pipe.
2. In a lighting fixture, the combination with a fixture support, of a frame encompassing said support, spaced therefrom and provided with a shoulder fixedly secured thereto; means detachable from said frame for securing the latter to said support; a reflector detachably mounted on said shoulder extending inwardly from said frame; a reflector support mounted on said fixture support provided with means for detachably securing said reflector thereto; and a source of light disposed below and outside of said reflector.

3. In a lighting fixture, the combination with a fixture support, of an annular frame encompassing said support spaced therefrom and provided with a shoulder fixedly secured thereto; means detachable from said frame securing the latter to said fixture support; a light transmitting reflector detachably disposed on said shoulder and extending inwardly; a reflector support secured to said fixture support; and a source of light disposed below and outside of said reflector.

4. In a lighting fixture, the combination with a fixture pipe, of an annular frame provided with a shoulder fixedly secured thereto; means detachable from said frame for detachably securing the latter to said fixture pipe; a reflector of conoidal form disposed on the shoulder of said frame; a reflector supporting shell detachably secured to said fixture pipe, and a source of light disposed below and outside of said reflector.

5. In a lighting fixture, the combination with a fixture pipe, of an annular frame provided with an inturned flange; a spider detachably secured to said frame and to said fixture support; a reflector of conoidal form having a lip at its inner edge and disposed on the flange of said frame; a reflector supporting shell detachably secured to said fixture pipe and provided with set screws for engagement with said lip; and a source of light secured to and depending from said fixture pipe.

6. In a lighting fixture, the combination with a fixture support, of a frame encompassing said support, spaced therefrom and provided with a shoulder; means for securing said frame to said support; a reflector detachably mounted on said shoulder extending inwardly from said frame; a reflector support mounted on said fixture support provided with means for detachably securing said reflector thereto; a source of light disposed below said reflector; a bowl supporting spider secured to said fixture support, and a bowl secured to said spider.

7. In a lighting fixture, the combination with a fixture support, of an annular frame encompassing said support spaced therefrom and provided with a shoulder; means securing said frame to said fixture support; a light transmitting reflector detachably disposed on said shoulder and extending inwardly; a reflector support secured to said fixture support; a source of light disposed below said reflector; a bowl supporting spider detachably secured to said fixture support; and a bowl detachably secured to said spider.

8. In a lighting fixture, the combination with a fixture pipe, of an annular frame provided with a shoulder; means for detachably securing said frame to said fixture pipe; a reflector of conoidal form disposed on the shoulder of said frame; a reflector

supporting shell detachably secured to said fixture pipe; a source of light disposed below said reflector; a bowl supporting spider detachably secured to said fixture support 5 and a bowl detachably secured to said spider.

9. In a lighting fixture, the combination with a fixture pipe, of an annular frame provided with an inturned flange; a spider detachably secured to said frame and to said fixture support; a reflector of conoidal form having a lip at its inner edge and disposed on the flange of said frame; a reflector supporting shell detachably secured 10 to said fixture pipe and provided with set screws for engagement with said lip; a bowl supporting spider; a shell detachably secured to said fixture and to said bowl sup-

porting spider; and a lamp socket detachably secured to said fixture pipe. 20

10. In a lighting fixture, the combination with a fixture support, of an annular frame encompassing said support spaced therefrom and provided with a shoulder; means securing said frame to said fixture support; 25 a light transmitting reflector detachably disposed on said shoulder and extending inwardly; a source of light disposed below said reflector; a bowl supporting spider detachably secured to said fixture support; 30 and a bowl detachably secured to said spider.

In witness that I claim the foregoing I have hereunto subscribed my name this 16th day of February, 1916.

EUGENE J. MEYBERG.
